UNITED STATES PATENT OFFICE.

KATHARINE WILLIAMS, OF NEW YORK, N. Y.

SKIRT-SUPPORTER AND SHOULDER-BRACE.

SPECIFICATION forming part of Letters Patent No. 629,641, dated July 25, 1899.

Application filed November 22, 1898. Serial No. 697,206. (No model.)

To all whom it may concern:

Be it known that I, KATHARINE WILLIAMS, a citizen of the United States, and a resident of the city, county, and State of New York, have 5 invented certain new and useful Improvements in Shoulder-Braces and Skirt-Supporters, of which the following is a specification.

My invention relates to improvements in devices for supporting women's skirts and 10 holding the body in the proper erect position; and it consists in certain novel features hereinafter described and claimed.

In the annexed drawings, which fully illustrate my invention, Figure 1 is a rear elevation 15 of a shoulder-brace and skirt-supporter embodying my improvements, dotted lines being used to indicate the position of the device on the wearer. Fig. 2 is a detail perspective view of a portion of the device, showing 20 a skirt-holding hook attached thereto; and Fig. 3 is a vertical section taken longitudinally through the hook shown in Fig. 2.

In carrying out my invention I employ a belt B, to which the straps A, of webbing or 25 other suitable material, are secured at the points A² adjacent to the center of the belt at the rear thereof. From the points A² these straps are passed upward (crossing at the point b) over the shoulders and thence brought 30 back under the arms to the belt at the points A². The secured ends of the straps project slightly below the edge of the belt to permit the attachment of a skirt-supporting hook C, as shown clearly in Figs. 2 and 3, and the free 35 ends are provided with series of perforations or eyelets a, which are engaged over the elbow c' of the hook C to fasten the straps. This construction, furthermore, permits an 40 easy and rapid adjustment of the device to the height of the wearer or the length of skirt desired.

The hook C shown in the drawings forms the subject-matter of a separate application for patent filed by me simultaneously herewith, and is provided with the skirt-sustaining loops c² and hook c²; but it will be readily understood that any hook which supports the skirts and may be engaged by the perforations in the ends of the straps may be substituted without involving a departure from 45 my invention.

My device is very light and simple and transfers the weight of the skirt from the hips to the shoulders. Passing over the shoulders and under the arms in the manner described 55 and shown, the device exerts no uncomfortable pressure on the breast, but applies a constant gentle backward pull on the shoulders and tends to expand the lungs.

Having thus described my invention, what 60 I claim, and desire to secure by Letters Patent, is—

The improved skirt-supporter and shoulder-brace herein described and shown comprising a belt, a pair of crossed straps passing over the shoulders and back under the arms, each strap having one end secured to the belt, and a skirt-supporting hook attached to and depending from the fast end of each strap, the free end of each strap being provided with a series of perforations adapted to 65 engage the hook at the fast end of the other strap. 70

Signed at New York, in the county and State of New York, this 19th day of October, 75 1898.

KATHARINE WILLIAMS.
